YORK

CARD-HOLDING CLIP

Application filed August 27, 1929. Serial No. 388,694.

This invention relates to improvements in card holding clips; and the invention has reference, more particularly, to card holding clips adapted for removable attachment to drawer partition walls, pigeon hole walls, shelves and for use in similar locations for carrying index data, identification data, price marks or like information.

This invention has for its principal object 10 to provide a simple, neat appearing and mechanically efficient card holding clip having a maximum card receiving and holding area, and a novel arrangement and construction of gripping means whereby the clip may 15 be firmly and securely engaged over a partition, shelf or like location in such manner as to conveniently display the data of the card or cards mounted in connection therewith.

This invention has for a further object, to 20 provide, in combination with the clip body a novel construction of yieldable or spring-like gripping elements or tongues, which may be readily adjusted for accommodation to partitions or shelves of various thicknesses with- 25 out risk of distorting or disturbing the card holding surfaces and retaining elements.

Other objects of this invention, not at this time more particularly enumerated, will be clearly understood from the following detailed description of the same.

Illustrative embodiments of this invention are shown in the accompanying drawings, in which:—

Figure 1 is a perspective view of a portion 35 of a drawer having a partition to which the novel card holding clip of this invention is applied; Figure 2 is a perspective view of the one form of the novel card holding clip per se, with cards removed; Figure 3 is a 40 vertical sectional view of the novel card holding clip as applied to a drawer partition or the like, and having cards mounted thereon.

Figure 4 is a perspective view of a modified form of the novel card holding clip per 45 se, with cards removed; and Figure 5 is a vertical sectional view of the same as applied to a drawer partition or the like, and with the cards assembled in mounted relation thereto.

Figure 6 is a vertical sectional view of

another modified form of card holding clip as applied to a drawer partition or the like, and with a card mounted thereon.

Similar characters of reference are employed in the hereinabove described views, 55 to indicate corresponding parts.

Referring to said drawings, the novel card holding clip, as shown more particularly in Figures 1 to 3 inclusive, comprises a clip body preferably made of springy or resilient 60 sheet metal and doubled upon itself to provide a medial portion 10 and side plates 11 and 12 depending respectively from the respective longitudinal margins of said medial portion 10. Preferably said side plates 11 65 and 12 are angularly related to said medial portion 10 so as to converge somewhat one toward the other. The metal at the juncture of said side plates 11 and 12 with the medial portion 10 is formed to provide longitudinal 70 ribs 13 which slightly overhang the outer face planes of said side plates 11 and 12 along the top margins thereof. These ribs 13 serve not only to stiffen the juncture of the side plates and medial portion, so that said parts 75 are reenforced against distortion, while at the same time said ribs serve as keepers for retained cards mounted on the side plates 11 and 12 against displacement, as will subsequently appear.

Said side plates 11 and 12 are of lengths greater than the length of the medial portion 10, thus providing at their respective ends wing-like free end portions, which are doubled back inwardly in outwardly spaced relation to the outer surfaces or faces of said side plates, thus forming vertical flanges 14 defining card receiving channels or grooves 15. In like manner the lower longitudinal marginal portion of each side plate 11 and 12 is 80 provided with an inwardly doubled back flange 16 to form a bottom card receiving channel groove cooperating with the channels or grooves 15 so as to receive and hold a card 17 upon the outer faces of the side 85 plates 11 and 12 respectively.

Stamped out of the body portions of said side plates 11 and 12 are spring gripping tongues 18 which are inwardly bent out of the planes of said side plates so as to incline in- 100

wardly and upwardly. The gripping tongues springing from the side plate 11 are opposed to the gripping tongues springing from the side plate 12, and the upper free ends of said opposed gripping tongues are related in converging relation one to the other. While the drawings show two gripping tongues 18 struck out from each side plate, it is not intended to limit the structure to such specific arrangement, since less or more than the two tongues thus shown may be employed. It will be obvious that the gripping tongues 18 provide a means for frictionally engaging a partition, shelf or the like, as, for example, the partition 19 as shown in the drawings. Said tongues 18 being movable relative to the side plates 11 and 12 are capable of being bent so as to easily and readily space opposed free ends thereof in more or less initial spaced relation, and consequently the tongues may be easily manipulated to adjust the same for gripping partitions, shelves or other walls of various thicknesses, without risk of distorting the desired flat plane surfaces of the side members 11 and 12 on which the cards 17 are mounted. Furthermore, owing to the fact that the opposed gripping tongues converge inwardly and upwardly from the open space between the side plates, application of the clip to a partition shelf or the like is greatly facilitated, while on the other hand the gripping action of the free ends of the tongues, when engaged with the partition, shelf or the like, offers a maximum frictional resistance to accidental displacement of the clip from such partition, shelf or the like.

Another advantage offered by the novel card holding clip construction of this invention is that the entire outer surface of the side plates may be utilized to back the cards 17 mounted thereon, thus permitting the use of comparatively large cards; and, furthermore, the gripping tongues 18, while struck out from the side plates, nevertheless do not obstruct or otherwise interfere with use of said side plates as a card supporting or carrying surface. The ribs 13, as above mentioned, serve as a detent for preventing cards from riding or shifting upwardly out of engagement with the bordering retaining flanges 14 and 16. It may also at times be desirable to mount cards at a height in excess of the height of the side plates, in which case the lower portions of such cards are securely engaged by the flanges 14 and 16, while the upper portion projects upwardly beyond the medial portion 10. When such large cards are employed, the ribs 13 tend to maintain the same slightly flexed and thus frictionally engaged with the vertical flanges 14 so as to be efficiently retained against accidental displacement from the holding clip.

Referring now to Figures 4 and 5 of the drawings, there is shown therein a card holding clip of the same general construction al-

ready above described, but having in connection with its medial portion 10 means for mounting a card on the surface thereof. This means comprises free wing-like extensions at the ends of said medial portion, which are inwardly doubled over in upwardly spaced relation to the top surface of said medial portion 10, thus forming card retaining flanges 20 to provide receiving grooves beneath which the ends of a card 21 may be engaged. To retain the card 21 against displacement, one or more stop tongues 22 may be struck upwardly out of the medial portion 10 adjacent to a longitudinal margin of the latter, and beneath which a longitudinal edge of the inserted card may be pinched, as shown more especially in Figure 5.

While in the previously described constructions of card holding clip, both side members 11 and 12 have been shown to have card retaining elements and gripping tongues 18, it is deemed within the spirit and scope of this invention to provide but one side member of the clip with card retaining elements, and to provide gripping tongue or tongues in connection with but one side member of the clip. This is illustrated in Figure 6 of the drawings wherein is shown a clip having a medial portion 23 and side members 24 and 25. The side member 24 is provided with marginal card retaining flanges 26 in connection with its end and bottom margins, to receive and hold a card 27. A resilient gripping tongue 28 is struck out of the side member 25 so as to project upwardly and inwardly within the space between the side members. When the clip so constructed is engaged over a partition 19, the side member 24 will bear on one side of said partition and the gripping tongue on the other side of the latter, thus frictionally engaging the clip with said partition. It will be obvious that the gripping tongue or tongues may be struck out of the side member 24 instead of the side member 25, should it be so desired, in which case the side member 25 would bear on one side of the partition 19 and the tongue or tongues on the opposite side thereof.

While in the accompanying drawings we have shown our invention and have described the same in the above specification merely in connection with illustrative preferred forms by way of example, it will nevertheless be obvious that many other alternations and variations may be made therein and in the mode of application or use thereof, which will still be comprised within its spirit. Generally speaking, we desire it to be understood that we do not limit ourselves to any specific form or embodiment except in so far as is specified in the herefollowing claims.

We claim:—

1. A card holding clip made of sheet metal comprising a body having a medial portion and side plates respectively extending angu-

larly in spaced apart relation from the longitudinal margins of said medial portion, at least one of said side plates having integral with its end and free longitudinal edges inwardly turned flanges spaced outwardly from the face thereof to form card receiving and retaining channels, and at least one of said side plates having inwardly and upwardly inclined resilient gripping tongue means projecting from its inner face for the purposes described.

2. A card holding clip made of sheet metal comprising a body having a medial portion and side plates respectively extending angularly in spaced apart relation from the longitudinal margins of said medial portion, at least one of said side plates having integral with its end and free longitudinal edges inwardly turned flanges spaced outwardly from the face thereof to form card receiving and retaining channels, said side plates each having inwardly and upwardly inclined resilient gripping tongue means projecting inwardly from the inner face thereof, and said gripping tongue means of the respective side plates being opposed one to the other in converging relation.

3. A card holding clip as defined in claim 2 having a longitudinally extending outwardly bowed rib at the juncture of said medial portion with said card holding side plate for the purposes described.

4. A card holding clip as defined in claim 2 having integral with the ends of said medial portion inwardly turned flanges spaced outwardly from the face thereof to provide additional card receiving and retaining channels, and a stop tongue struck upwardly from the body of said medial portion adjacent a longitudinal marginal portion thereof.

5. A card holding clip made of sheet metal comprising a body having a medial portion and side plates respectively angularly extending in spaced apart relation from the longitudinal margins of said medial portion, each side plate having in doubled back spaced relation to its outward face marginal flanges springing from its end and free longitudinal margins to form card receiving and retaining means, and said side plates having struck inwardly therefrom upwardly projecting gripping tongue means in opposed converging relation one to the other.

6. A card holding clip made of sheet metal comprising a body having a medial portion and side plates respectively angularly extending in spaced apart relation from the longitudinal margins of said medial portion, each side plate having in doubled back spaced relation to its outward face marginal flanges springing from its end and free longitudinal margins to form card receiving and retaining means, said side plates having struck inwardly therefrom upwardly projecting gripping tongue means in opposed

converging relation one to the other, and longitudinally extending outwardly bowed ribs at the junctures of said side plates with said medial portion to stiffen the clip and serve as stops against displacement of cards from the receiving and retaining means of said side plates.

7. A card holding clip as defined in claim 5 having integral with the ends of said medial portion inwardly turned flanges spaced outwardly from the face thereof to provide additional card receiving and retaining means, and a stop tongue struck upwardly from the body of said medial portion adjacent a longitudinal marginal portion thereof.

In testimony, that we claim the invention set forth above we have hereunto set our hands this 16th day of August, 1929.

JOSEPH A. UNDERHILL.
